United States Patent Office

Des. 184,270
Patented Jan. 13, 1959

184,270

WATCH CASE

Adolph Winkler, Jamaica Estates, N. Y., assignor to Hilton Watch Co., New York, N. Y., a corporation of
New York

Application December 16, 1957, Serial No. 48,923
Term of patent 14 years

(Cl. D42—8)

FIG.3

Fig. 1 is a plan view of a watch case, showing my new design;

Fig. 2 is a right side elevational view; and
Fig. 3 is a left side elevational view thereof.

I claim:

The ornamental design for a watch case, as shown.
